His ATTORNEY.

UNITED STATES PATENT OFFICE.

FRANK KROPP, OF WAMEGO, KANSAS.

WALL.

Application filed March 28, 1927. Serial No. 178,925.

My invention relates to improvements in walls. It relates particularly to walls composed of hollow building blocks laid in rows one above the other.

5 One of the objects of my invention is to provide a novel wall of the kind described, which is, interiorly, well ventilated from top to bottom and end to end, which will permit a minimum amount of moisture to pass 10 through the wall, which has novel means for tying the blocks together without interfering with the interior ventilation, which is very strong, durable, and easy to lay, and which at both sides presents a good appearance.

15 The novel features of my invention are hereinafter fully described and claimed.

In the accompanying drawing, which illustrates the preferred embodiment of my invention,

20 Fig. 1 is a perspective view of my improved wall, partly broken away.

Fig. 2 is a section on the line 2—2 of Fig. 1.

Fig. 3 is a perspective view of one of my improved blocks.

25 Fig. 4 is a perspective view of one of the tying members.

Similar reference characters designate similar parts in the different views.

My improved building block comprises, 30 preferably, a rectangular hollow block 1, preferably composed of sand and cement, or other material adapted to be molded, and which is open at one vertical side and closed at all of its other sides and ends.

35 Each of the blocks 1 has its inner walls diverging toward the open side of the block, enabling it to be readily removed from the mold, and, as will be hereinafter described, providing means for preventing the accumulation of water in the blocks, after they have been 40 laid in the wall.

Each block 1 is preferably provided with a central vertical partition 2, which is substantially double the thickness of one of the end walls.

45 In constructing my improved wall the blocks 1 are laid in two parallel vertical spaced tiers having between them a vertical air space 3, which is substantially co-extensive with the height and length of the tiers.

Each tier comprises horizontal rows of the blocks, disposed one above the other, the adjacent rows being laid so as to break the joints at the central portions of the blocks. The 55 blocks being of equal length, the partition 2

of each block will align vertically with the adjacent ends of the blocks in the row next above and in the row next below. This affords great strength to the wall.

The blocks are laid in suitable cementing 60 material, such as cement 4, the open sides of the blocks of each tier being next adjacent to the air space 3. This provides a wall having no openings at either side, and affords a broad surface on the upper side of each block 65 upon which to lay the cement 4. Each block of each tier is spaced throughout from the blocks of the opposite tier.

When two corresponding rows of blocks have been laid in the two tiers, tying means 70 are laid upon the upper sides of the two rows, said tying means extending across the air space 3, and being embedded in the layer of cement which is then applied to the upper sides of the two rows.

75 The tying means may comprise a plurality of tying members, each of which has, when laid in the wall, a laterally turned portion disposed in each tier. The preferred form of tying member comprises an S-shaped 80 wire 5 of suitable thickness disposed transversely, as shown in Figs. 1 and 2, the tying member being spaced from the outer sides of the wall.

85 After the tying members 5 and the cement 4 have been laid upon the two rows of blocks, the next two rows of blocks are next laid thereupon so as to break the joints with the row next below, as has been described. Cement 4 and tying members are then placed 90 upon the two rows last laid, after which the succeeding pairs of rows are laid in the manner just herein before described until the wall has been finished.

95 By having the inner walls of each block diverging toward the open side of the block, when the blocks are laid in the wall with the open sides next to the air space 3, the upper side of the bottom of each block will slant downwardly from the closed outer side 100 of the block to the air space 3, whereby any moisture which may be absorbed from the exterior of the wall will not collect in the blocks, but will run therefrom into the air space 3 to the bottom of the latter from which it 105 may be discharged at one or both ends thereof.

By having each block of each tier spaced throughout from the blocks of the opposite tier, the moisture absorbed by the blocks 110

of the outer tier is not conveyed thereby to the blocks of the inner tier.

The laterally turned portions of the tying members 5 being embedded in the cementing material 4 in each of the tiers provides an efficient means for securely tying together the two tiers of blocks.

The provision of the vertical air space 3 between the tiers substantially co-extensive 10 with the length and height of the wall affords good ventilation in the wall and a good insulator for preventing the conduction of heat or cold through the wall, as well as serving as a means for preventing moisture 15 passing through the wall.

I do not limit my invention to the structure shown and described, as many modifications, within the scope of the appended

claims, may be made without departing from the spirit of my invention.

What I claim is:—

In a wall, two parallel vertical spaced tiers 20 of hollow blocks, an air space between the tiers, each tier comprising horizontal rows of blocks cemented together one above the other, each block being open at the side next adjacent to the air space and closed at all of its other sides, the upper side of the bottom of each block inclining downwardly to said air space, each block being spaced 25 throughout from the blocks in the opposite tier, and tying means across said air space connecting said tiers.

In testimony whereof I have signed my name to this specification.

FRANK KROPF.
